UNITED STATES PATENT OFFICE.

HAROLD A. YARNELL, OF LOS ANGELES, CALIFORNIA, ASSIGNOR TO PACIFIC WIRELESS TELEGRAPH COMPANY, OF LOS ANGELES, CALIFORNIA, A CORPORATION OF WASHINGTON.

ELECTRICAL INTERRUPTER AND RECTIFIER.

No. 856,933.

Specification of Letters Patent.

Patented June 11, 1907.

Application filed June 16, 1905. Serial No. 265,480.

To all whom it may concern:

Be it known that I, HAROLD A. YARNELL, a citizen of the United States, residing at Los Angeles, in the county of Los Angeles and 5 State of California, have invented a new and useful Electrical Interrupter and Rectifier, of which the following is a specification.

This invention relates to a device for automatically interrupting an electric current, being adapted for interrupting both direct and alternating currents and also for rectifying an alternating current.

The device is adapted for interrupting the circuit through the induction coil of the 15 transmitter in wireless telegraph systems; it is also adapted for use with X-ray or other apparatus; and generally for the rectification of alternating currents.

The main object of the invention is to provide a device of the character described which is operated without mechanically moving parts, which is very simple and inexpensive in construction, which is inexpensive to operate and maintain, and which is durable in use. 25 The accompanying drawings illustrate the invention, and referring thereto:

Figure 1 is a vertical cross section through one form of the invention. Fig. 2 is a vertical cross section, enlarged, through one form of 30 tubular electrode chamber. Fig. 3 is a view similar to Fig. 2, showing another form of electrode. Fig. 4 is a cross section showing another form of electrode, only the lower portion of the tubular chamber being shown. 35 Fig. 5 is a view similar to Fig. 4, showing another form of electrode. Fig. 6 is a section on line x^6 — x^6 , Fig. 5. Fig. 7 is a vertical cross section through another form of electrode, electrode chamber, and attachments, 40 a portion of the external vessel being shown. Fig. 8 is a detail in perspective of the cap for the electrode chamber of Fig. 7. Fig. 9 is a perspective of the clamp, shown in Fig. 7, for connecting the carbon electrode with its support. Fig. 10 is a view similar to Fig. 7 showing another form of electrode chamber and an automatic electrode feed. Fig. 11 is a perspective in detail of the electrode and connections of Fig. 10. Fig. 12 is a view 45 similar to Fig. 7 showing another form of electrode chamber and attachments. Fig. 13 is a detail in perspective of the lower end of the electrode support shown in Fig. 12.

Briefly the invention comprises two electrodes, one of which is a liquid, and means for 55 limiting the effective contact of the liquid electrode with the other electrode.

In its preferred form, the invention comprises a cell or jar 1 of glass with a cover 2 of insulating material, the latter having rubber 60 lugs 3, which grip under a flange 4 formed near the upper rim of the jar, the cover 2 having a groove fitting the rim of the jar so that the cover is detachably held in place. The jar contains a liquid 5, consisting preferably 65 of a solution or mixture of sulfuric acid and water and immersed therein, near the bottom of the jar is a lead terminal 6 supported by a leg 7, the upper end of the leg being supported by the cover 2. The upper end of the leg 70 has a binding post 8 for the attachment of a conducting wire 9. Suspended in the liquid and supported by the cover 2 is an electrode chamber or shell 10, preferably of glass, which may be constructed in various ways. 75 Within the shell is an electrode. The simplest form is shown in Fig. 2, in which the shell 10 has a flat bottom with a central orifice 11. The upper end of the shell is closed by a cover 12 having orifices 13. Suspended 80 near the lower end of the shell by a leg 14 is an electrode 15, the leg and electrode being both preferably formed of lead. The leg 14 extends up through the cover 12 and is perforated to receive a conducting wire 16, the latter being held in place by a binding screw 17. In using this form of apparatus in the transmitting station of wireless telegraph systems, I have connected the wire 9 with one terminal of a circuit using alternating current and connected the wire 16 with one pole of the primary of the induction coil; the other pole of the primary was connected to the other terminal of the supply circuit. Upon 90 closing the circuit through the apparatus, the current passes through the terminal 6 and through the electrolyte 5, and through the electrode 15 and primary of the induction coil. The effective contact of the electrolyte with the electrode 15 is limited by the orifice 11, and upon the passage of the current, the liquid is forced away from the lower end of the electrode 15, forming a bubble so to speak, which automatically breaks the circuit, which however is immediately closed by 95 reason of the destruction of the bubble, the 100 105

liquid renewing itself in contact with the electrode. This action takes place many times in quick succession whenever the circuit through the device is closed, even if closed only for an instant. This automatic interruption occurs also when a direct current is used. In addition to this automatic interruption of the current, I have found in practice that the device, when used with an alternating current acts also as a rectifier, thus making it possible to use the device for converting an alternating current into a direct current. There is thus a wide field for use, as a rectifier, the device not being confined exclusively to uses in which its function is that of an interrupter.

In the form shown in Fig. 3, the electrode 15 has a convex lower face which spreads out the bubble. The tube is provided with orifices *a*, and a petticoat *b*, with grooves *c*, and depending cones *d*. Below the petticoat is a smaller one *e*, of similar construction, the tube having orifices immediately above. If the liquid should in continuous or rapid work, 25 accumulate in the tube, it will discharge through the orifices *f* and *a* and flow down the grooved petticoats and collect in drops on the cones *d*, dropping therefrom into the body of liquid in the jar. Fig. 1 shows the 30 tube with only one petticoat, and one or more may be employed as desired. The petticoats are sustained by rings *g* clamped to the tube. By thus causing the liquid to drop from the petticoats instead of running in a 35 stream into the liquid, short circuiting is prevented. Fig. 4 shows the electrode provided with a concave lower face which tends to concentrate the bubble at the center of the electrode. The orifices *h* allow the 40 gases formed by the action of the current upon the electrolyte to escape.

Fig. 5 shows another form of electrode comprising a ring 18, which closely fits the bore of the shell 10, and is connected to the leg 14 by three arms 19, which are formed with a split collar 20, the latter being clamped to the leg 14.

Fig. 7 shows another form in which the electrode comprises a carbon 21, the lower 50 end of which protrudes through an orifice in the rounded end of the tube 22. In this form the effective contact of the electrolyte with the electrode is limited to that portion of the electrode that protrudes below the 55 tube. As the carbon burns away during continued use, it is advisable to provide means for adjusting it and to that end it may be supported by a bifurcated conducting rod 23, the legs of which are securely connected 60 to the carbon by a clamp 24; one leg 25 preferably having a foot 26 which hooks under the edge of the clamp. The shank of the rod 23 is screw-threaded and is supported by a cover 24^a formed of an insulating material, 65 which may be detachably fastened to the up-

per end of the tube 22 by spring clips 27, which have kinks 28 engaging in an annular groove 29. One of the clips 27 is provided with a binding post 30. The upper end of the conducting rod 23 is electrically connected with the binding post 30 and has a thumb piece 31 and by turning the same, the carbon 21 may be adjusted to a nicety. This form when used causes the bubble to form around the protruding end of the carbon. 75

Fig. 10 shows a form in which the carbon electrode is self-adjusting. In this form the shell 22 at its lower end has a tapered orifice in which lies the tapered lower end of carbon 21, the diameter being less than the diameter 80 of the carbon, so that the carbon will be supported by the tube, and will drop gradually as it burns away at its lower end. A disk 32 is arranged in the tube 22 and is prevented from slipping down by the contracted end 85 of the tube. The disk 32 has an orifice 33, which allows the carbon 21 to move down freely. Attached to the disk 32 is a connection strip 34, the upper end of which has a binding post 35. Within the tube 22 at its 90 upper end, is a block 36 through which the strip 34 loosely passes and is centrally perforated to receive the upper end of carbon 21. The block 36 is supported on the carbon by a split collar 37, and the block 36 acts as a 95 weight to hold the lower end of the carbon in its seat and prevent it jumping upward, and also serves to guide the upper end of the carbon, the block 36 freely moving down in the tube as the carbon burns away. The 100 disk 32 is provided with orifices 33^a for the escape of gas, which might otherwise collect in the bottom of the tube.

Fig. 12 shows another form in which the carbon is self-feeding but is supported by an 105 abutment comprising a glass cone 38 which is suspended below the tube by means of straps 39 which depend from an external tube 40; the latter surrounding the tube 22, there being preferably a slight space between the side walls of the two tubes. Around the upper end of the external tube 40 is a split collar 41 with external tapered threads, the collar being clamped to the tube 40 by a nut 42 with internal tapered threads. 115 A split collar 43 having external tapered threads is clamped to the inner tube 22 by a nut 44, having internal tapered threads; and the collar 41 has internal threads which engage external threads on the collar 43. 120 Otherwise, the construction of the inner tube, carbon and other parts, is similar to the construction shown in Fig. 7. In this form, the lower end of the carbon rests upon the rounded tip of the cone 38, and as it burns away, 125 the carbon sinks so that its lower end always rests upon the cone and thus maintains constantly a definite area of exposed carbon, which protrudes below the bottom of the tube 22. By screwing the inner tube up or 130

down, the protruding area of the carbon and consequent effective contact of the electrolyte may be regulated to the desired point.

While I have shown and described several forms of my invention, it should be understood that the invention is not restricted to the specific forms shown.

What I claim is:—

1. An electrical interrupter and rectifier comprising a liquid, a shell with a perforated end immersed in the liquid, an electrode in the shell with its end projecting through the perforation in the shell, a tube outside of the shell, the lower end of the tube having arms which support a cone upon which cone the lower end of the electrode rests, and means for securing vertical relative adjustment between the tube and shell whereby the effective contact area of the lower end of the electrode may be regulated.
2. An electrical interrupter and rectifier comprising a liquid, a shell with a perforated

end immersed in the liquid, an electrode in the shell with its end projecting through the perforation in the shell, a tube outside of the shell, the lower end of the tube having arms which support a cone upon which cone the lower end of the electrode rests, means for securing vertical relative adjustment between the tube and shell whereby the effective contact area of the lower end of the electrode may be regulated, a conducting rod within the shell extending from the upper end of the shell to near the lower end of the shell, and means at the upper end of the shell for supporting the conducting rod.

In testimony whereof, I have hereunto set my hand at Los Angeles California this 9th day of June 1905.

HAROLD A. YARNELL.

In presence of—

GEORGE T. HACKLEY,
ARTHUR P. KNIGHT.
